(57) **CLAIM**

I claim the ornamental design for a flashlight, as shown and described.

DESCRIPTION

FIG. 1 is a front, bottom, right side isometric view of the flashlight;

FIG. 2 is a right side view thereof;

FIG. 3 is a top view thereof;

FIG. 4 is a left side view thereof;

FIG. 5 is a bottom view thereof;

FIG. 6 is a front view thereof; and,

FIG. 7 is a back view thereof.

The broken lines in the drawings are for illustrative purposes only and form no part of the claimed design.
